UNITED STATES PATENT OFFICE

108,339

DESIGN FOR A PICTURE FRAME

Murray Mitchell, New York, N. Y.

Application October 16, 1937, Serial No. 72,232

Term of patent 7 years

To all whom it may concern:

Be it known that I, Murray Mitchell, a citizen of the United States, residing at New York, county and State of New York, have invented a new, original, and ornamental Design for a Picture Frame, of which the following is a specification, reference being had to the accompanying drawing, forming a part thereof.

In the drawing:

Fig. 1 is a plan view of a picture frame showing my new design, and

Fig. 2 is a sectional elevation thereof, the section being taken on the line 4—4 of Fig. 3.

The lined, hatched portions in the drawing indicate a contrasting color to the rest of the frame.

I claim:

The ornamental design for a picture frame, as shown and described.

MURRAY MITCHELL.
